LINT REMOVER FOR KNITTING MACHINES

William Sherman Sharp, Yankee Spring Township, Barry County, Mich., assignor of one-half to Harold E. Sharp, Middleville, Mich.

Application September 8, 1947, Serial No. 772,619

4 Claims. (Cl. 66—168)

1

This invention is directed to a lint remover for knitting machines.

In knitting machines the thread or yarn going to the needles is made up of fibers, and in the operation of knitting, fibers are loosened from the yarn and separated therefrom to collect at or in back of the thread guides, with an accumulation of fibers in the form of "lint" as it is known. It is an object and purpose of the present invention to provide a simple attachment for knitting machines, particularly those of circular type, which may be added to a knitting machine in use, or may be supplied to new knitting machines before they have been used. With this attachment, periodically and at regular intervals, air is projected against the lint back of the thread guides to blow it away. Such blowing of the air occurs at generally equally spaced times when the machine is in operation, and may be made to occur once with each rotation of the cylinder of the machine, or more frequently in such rotation is a more frequent removal of the lint by projection of air under pressure against it is desired.

An understanding of the invention may be had from the following description, taken in connection with the accompanying drawings, in which:

Fig. 1 is a perspective view of a circular knitting machine having my invention applied thereto.

Fig. 2 is a fragmentary enlarged elevation of the mechanism at one of a plurality of knitting stations around the dial of the machine, at each of which air under pressure is to be periodically projected against lint at the back of the thread guide at each of said knitting stations.

Fig. 3 is a plan view of the structure shown in Fig. 1, and

Fig. 4 is a fragmentary enlarged elevation illustrating the mechanism used for controlling and periodically projecting compressed air at the knitting stations.

Like reference characters refer to like parts in the different figures of the drawings.

The circular knitting machine is a well known structure. Enough of it is illustrated and described herein to show the environment of the invention and how it is used and attached to the knitting machine.

In the circular knitting machine, an outer fixed frame includes upper and lower rings 1 and 2 spaced from each other and connected by vertical plates 3. Within the rings the cylinder of the machine, which is turned rapidly about a vertical axis is mounted for rotation. It includes

2

a lower ring 4 within the fixed frame ring 2 and an upper ring 5. Rings 4 and 5 are connected by vertical connections 6 so that both upper and lower rings move together. The cylindrical needles of the machine are indicated at 7, at the inner side of the upper ring 5 of the cylinder. These cooperate with dial needles carried on a circular dial 8 horizontally located within and in a plane above the upper ring 5.

10 In the structure of the machine at a plurality of spaced distances around the dial plate 8, brackets 9, with guide eyes therein for guiding the yarn or thread going to the machine, are fixed, and in association with each is a thread guide 10 15 disposed in proper relation to the needles at the inner side of the upper cylindrical ring 5 and near the meeting ends of the series of needles on the cylinder and dial.

Such structure of a circular knitting machine 20 is old and well known, and the detail of structure and how it is operated need not be further described, as all skilled in the art are familiar with it. It is enough to say that the cylinder, and the needles carried thereby, is rotated rapidly within 25 the outer frame rings 1 and 2, and the thread at the several stations is guided to and is received by the needles so that a continuous cylindrical knitted web is produced in the machine operation.

During such knitting lint from the thread collects in bunches back of the thread guides 10. The present invention is directed to simply, readily, easily and automatically remove said lint before it can collect in any considerable quantities.

With my invention a supporting spider of flat 35 cross bars 11 is mounted horizontally above the dial, the arms being supported at their outer ends by vertical posts 12 connected to the upper frame ring 4 as shown. Such spider and posts 12 in practice may be a part of a circular knitting machine. But if in some makes of such knitting machines they are not present, they are readily supplied to serve as a support for a tubular manifold 13, of ring shape, preferably, which is fixed 40 to and carried at the upper side of the spider.

45 From the manifold 13, outlet tubes 14, connected thereto at their upper ends, extend outwardly and downwardly, and at their lower free ends are each equipped with an air-passing nozzle 15 (Fig. 2). Such nozzles are located directly adjacent the thread guides 10 and the tubes 14 are 50 curved and shaped as shown so that air passing from the nozzles is directed in horizontal paths at the back of the thread guides against any lint there collected. There is one of the tubes 14 for 55 each of the thread guides as shown.

The tubular manifold 13 is supplied with compressed air through an inlet supply pipe 16 which extends downwardly at the outer side of the machine and at its lower end is connected with a valve housing 17. Compressed air from any suitable source thereof is carried to the housing 17 through a pipe 18. If there was no control for the air within the housing 17, it would flow continuously from the nozzles 15.

The air is controlled within the housing 17 by a valve which has a stem 19 extending below the lower side of such valve housing. The valve housing is carried on a bracket 20 secured to the lower frame ring 2. At the under side of the housing 17 an L-shaped bracket 21 is secured, at the lower end of which a horizontal bar 22 is pivotally connected at one end. This bar, between its ends, extends across the lower end of the valve stem 19. At its free end bar 22 has a horizontal roller 23 which extends across the upper side of the lower ring 4 of the cylinder. At the upper side of the ring 4 a block 24 is secured, which has an inclined upper side.

When, in the rotation of the cylinder, the ring moving in a counter-clockwise direction, the thinner end of the block 24 comes to the roller 23, it moves thereunder and the roller rides upwardly on the inclined upper side of said block, lifting the valve stem 19 momentarily, or until said cam block 24 has passed by the roller 23. During such momentary lifting of the valve stem 19 and the valve connected therewith, there is a passage of compressed air from the outer supply pipe 18, through the housing 17, the pipe 16 to the manifold 13, and thereupon through all of the nozzle pipes 14. When this occurs, air is momentarily projected outward from each of the nozzles 15. This blows any collected lint away. As each of the knitting stations is provided with a nozzle 15, all of the lint at all of said stations is speedily removed by the compressed air jets coming thereagainst.

It is of course obvious that more than one of the valve lifting blocks 24 may be connected with the lower ring 4 of the cylinder, so that instead of the air being projected to blow the lint away once with each cylinder rotation, such lint may be blown two or more times during each rotation of the cylinder. However, I have found in practice that the lint removal once during each cylinder rotation is all that is generally required.

The attachment described consists of few parts which may be made and installed readily and economically. The tubes 14 being bendable, the nozzles 15 may be located at the best places to direct compressed air against lint. Such attachment is applicable to substantially all circular knitting machines at any time during the life of such machine. In practice it has proved very desirable and effective.

The invention is defined in the appended claims and is to be considered comprehensive of all forms of structure coming within their scope.

I claim:

1. In a structure as described, a circular tubular manifold adapted to be mounted at the upper end of a circular knitting machine, a plurality of tubular outlets connected with said manifold spaced from each other around the manifold, each outlet tube being arranged to extend to a knitting station of a circular knitting machine back of the thread guide therein, a tubular inlet connected with the manifold adapted to extend downwardly to the lower portion of the frame of a circular knitting machine, a valve housing connected to the lower end of said inlet tube, means for supplying compressed air to said valve housing, a movable stem extending below the valve housing, upward movement of which opens a passage for compressed air through said tubular inlet to the manifold and thence out through the outlet tubes, and a lever pivotally mounted at one end carried by said valve housing and extending underneath said stem, upper movement of the lever opening passage in the valve housing for flow of compressed air.

2. A structure as defined in claim 1, and a roller connected to the other end of said lever extending laterally therefrom and adapted to lie over the upper side of the lower member of the rotating cylinder of a circular knitting machine, and an inclined cam member adapted to contact said roller member to ride underneath and momentarily lift said roller with each rotation of the cylinder.

3. The combination with a knitting machine having a rotary member of a lint remover comprising, a hollow manifold, a plurality of tubular outlets connected to said manifold and each extending to knitting station of the machine, a conduit connecting said manifold with a source of compressed air, a valve in said conduit and means on the rotary member for periodically opening said valve in timed relation to the rotation thereof.

4. The combination with a knitting machine having needles, a rotary needle operating member and a plurality of thread guides, of a hollow manifold, a plurality of tubular outlets extending from said manifold, one to each of said thread guides and each having a nozzle directed between a respective thread guide and the adjacent needles, and means to pass compressed air through said manifold and outlets and from said nozzles.

WILLIAM SHERMAN SHARP.
